UNITED STATES PATENT OFFICE.

ADAM NICKEL, OF NEW YORK, N. Y., ASSIGNOR TO WESSELL, NICKEL & GROSS, OF NEW YORK, N. Y., A CORPORATION OF NEW YORK.

REPEATING ACTION FOR GRAND PIANOS.

No. 902,439.

Specification of Letters Patent.

Patented Oct. 27, 1908.

Application filed July 28, 1908. Serial No. 445,742.

To all whom it may concern:

Be it known that I, ADAM NICKEL, a citizen of the United States, residing at New York city, Manhattan, county and State of New York, have invented new and useful Improvements in Repeating Actions for Grand Pianos, of which the following is a specification.

This invention relates to a repeating action for grand pianos which will quickly and smoothly re-assume an operative position upon a partial release of the key, so that the action responds delicately to the touch.

In the accompanying drawing: Figure 1 is a side elevation, partly in section, of my improved grand piano action, showing the normal position of the parts, and Fig. 2 a similar view, showing the position of the parts upon a depression of the key.

The key 10, through capstan 11, tilts support 12 on center 13, as usual. To forward end of support 12 is pivoted at 14, the lower member 15 of a jointed jack, such member having a lower forwardly extending toe 16 adapted to be engaged by an escapement-button 17. To the upper end of member 15 is pivoted at 18 the upper jack-member 19 having an upper rearwardly extending tappet 20. Member 19 is pivoted at 21 to the forward end of a repeating lever 22, the rear end of which is pivoted at 23 to support 12. Lever 22 is provided with a cushioned rest 24 for the knuckle 25 of hammer 26.

Lower jack-member 15 is provided with a regulating button 27 which so engages an abutment 28 of support 12, that normally a reentrant angle is formed at the knee between jack-members 15, 19.

To support 12 is fulcrumed at 29, an auxiliary lever 30 which extends beneath lever 22 and is slotted near its forward end as at 31, to accommodate jack-member 19. In front of such member, lever 30 is curved upwards to engage with its cushioned end 32 a regulating screw 33 tapped into hammer-flange 34. Directly back of member 19 there is formed on lever 30, an upwardly extending cushioned shoulder 35 adapted to form a support for tappet 20. A spring 36 interposed between lever 30 and support 12 tends to normally force lever 30 upwards and thereby press shoulder 35 against tappet 20. The tension of this spring may be adjusted by regulating screw 37 tapped into support 12 and engaging a tail 38 of the spring.

During the normal position of the parts, shoulder 35 of lever 30 is, by spring 36, pressed against tappet 20 of member 19, so that regulating button 27 of member 15 is held against abutment 28 and the desired re-entrant angle is formed at the jack-knee.

Upon the depression of the key, support 12, together with the parts connected thereto, is swung on fulcrum 13 to advance the hammer towards string 39. During the first part of this movement, auxiliary lever 30 will strike abutment 33, which will check its rise. As the action continues its upward movement, repeating lever 22 will be swung away from lever 30, thus taking the pressure of spring 36 off tappet 20 and consequently off the jack. Shortly before the hammer strikes string 39, regulating button 17 will engage toe 16, so as to bend the jack forward at its knee to such an extent, that pivot 18 is advanced slightly in front of a line connecting pivots 14 and 21, (full lines, Fig. 2). After the hammer has struck the string and while the key remains depressed, the hammer will, on falling back by its weight, lower repeating lever 22. This lever will, in turn, bend the jack still further forward, the collapse resulting being limited by a cushion 40 fitted into the front of slot 31. As the jack is thus bent forward, tappet 20 will be tilted into contact with shoulder 35 of lever 30, as shown by dotted lines in Fig. 2.

Upon the partial release of the key, the action will swing down on fulcrum 13, with the exception of lever 30, which, under the influence of spring 36, will be held up against abutment 33. In this way shoulder 35 constitutes a fixed support for tappet 20, so that the weight of the hammer co-acting with that of lever 22, will turn upper jack-member 19 backward on its fulcrum 21, thus returning both members of the jack to their operative position. During this movement, the straightening out or unbending of the jack is assisted by spring 36, which, by tending to lower support 12, will exert a downward pull on the lower jack-member. Thus the parts are returned to their repeating position in a quick and smooth manner. Upon the full release of the key, the entire action is lowered into the normal position illustrated in Fig. 1.

I claim:

1. A repeating action for grand pianos, comprising a support, a lower jack-member, an upper jack-member pivoted to the lower

- member, a repeating lever, and a spring-influenced auxiliary lever adapted to operatively engage said upper member, substantially as specified.
5. A repeating action for grand pianos, comprising a support, a lower jack-member, an upper jack-member pivoted to the lower member and having a tappet, a repeating lever, and a spring-influenced auxiliary lever adapted to engage said tappet, substantially as specified.
10. 3. A repeating action for grand pianos, comprising a support, a lower jack-member, an upper jack-member pivoted to the lower member and having a tappet, a repeating lever, and a spring-influenced auxiliary lever having a shoulder adapted to engage said tappet, substantially as specified.
15. 4. A repeating action for grand pianos, comprising a support, a lower jack-member, an upper jack-member pivoted to the lower member, a repeating lever, an auxiliary lever adapted to operatively engage said upper member, and a spring intermediate the support and auxiliary lever, substantially as specified.
20. 5. A repeating action for grand pianos, comprising a support, a lower jack-member, an upper jack-member pivoted to the lower member, a repeating lever, a spring-influenced auxiliary lever adapted to operatively engage said upper member, and an abutment for said auxiliary lever, substantially as specified.
25. 6. A repeating action for grand pianos, comprising a support, a lower jack-member, an upper jack-member pivoted to the lower member, a repeating lever, and a slotted spring-influenced auxiliary lever that straddles the upper jack-member and operatively engages the same, substantially as specified.
30. 7. A repeating action for grand pianos, comprising a support, a lower jack-member, an upper jack-member pivoted to the lower member, a repeating lever, and a spring-influenced auxiliary lever pivoted to the support, said auxiliary lever being adapted to operatively engage the upper jack-member, substantially as specified.
35. 8. A repeating action for grand pianos, comprising a support, a lower jack-member having a forwardly projecting toe, an upper jack-member pivoted to the lower member and having a rearwardly projecting tappet, a repeating lever pivoted to the upper jack-member, a regulating button adapted to be engaged by the toe, and a spring-influenced auxiliary lever adapted to engage the tappet, substantially as specified.
40. 9. A repeating action for grand pianos, comprising a support, a lower jack-member having a forwardly projecting toe, an upper jack-member pivoted to the lower member and having a rearwardly projecting tappet, a repeating lever pivoted to the upper jack-member, a regulating button adapted to be engaged by the toe, a spring-influenced auxiliary lever adapted to engage the tappet, and an adjusting screw adapted to be engaged by the auxiliary lever, substantially as specified.
45. 10. A repeating action for grand pianos, comprising a support, a lower jack-member having a forwardly projecting toe, an upper jack-member pivoted to the lower member and having a rearwardly projecting tappet, a repeating lever pivoted to the upper jack-member, a regulating button adapted to be engaged by the toe, a spring-influenced auxiliary lever adapted to engage the tappet and having an upwardly bent forward end, and an adjusting screw adapted to be engaged by said end, substantially as specified.
50. 11. A repeating action for grand pianos, comprising a support, a repeating lever, a connecting jointed jack having a lower member and an upper member, an escapement for the lower member, spring-influenced means for tilting the upper member, and means for withdrawing said tilting means from engagement with said upper member, substantially as specified.

Signed by me at New York city, (Manhattan,) N. Y., this 27th day of July, 1908.

ADAM NICKEL.
